METHOD OF AND MACHINE FOR MULTIPLE
WEB FABRIC PRINTING

James F. Foley and George E. Couillard, Augusta,
Ga., assignors to United Merchants & Manufacturers, Inc., New York, N. Y., a corporation
of Delaware

Application September 28, 1934, Serial No. 746,006

5 Claims. (Cl. 101—178)

Our present invention relates generally to the art of fabric printing and more particularly to an improved method of and apparatus for simultaneously printing designs upon a plurality of webs.

At the present time it is the practice in the art of fabric printing to print on one machine designs in single or multi-colors upon a single web only, with the consequence that the daily output per machine is limited.

The prime object of the present invention is to provide a fabric printing machine wherein a plurality of fabric webs may be printed simultaneously in one or more colors, and with the same or different patterns or designs, so that the daily output per machine will be increased two, three or more fold with its attendant and other advantages and savings.

Another object of the invention includes the provision of a construction and arrangement of parts for simultaneously printing the several webs while preventing the webs from coming into contact with each other during the printing process, with the consequent advantages that printing dyestuffs of different or opposing chemical characteristics may be used simultaneously on the same machine, and there can be no "marking off" which would result from one wet web contacting another.

Still another object of the invention is to provide for visibility at all times during the printing process of the different printed webs.

Still another object of the invention is to provide for using printing elements or rollers of varying circumferences, that is, the use of rollers or printing elements of one dimension on one web, and printing elements or rollers of a different dimension on another or other webs.

The foregoing and other objects and advantages of the invention will become more apparent and will be pointed out during the course of the following detailed description of the accompanying drawings, in which we have shown, for the purposes of illustration, the invention as applied to or used in connection with a known type of printing machine, namely, a "cylinder" machine; but it is to be understood that the invention may be practiced otherwise, or with other types of machines without departing from the spirit thereof.

Fig. 1 is a diagrammatic view of a cylinder type of fabric printing apparatus and dryer showing one form of our invention applied thereto;

Fig. 2 is an enlarged end elevation of the printing cylinder frame and printing rolls of Fig. 1;

Fig. 3 is a fragmentary front elevation of the driving means for the printing rolls;

Fig. 4 is a diagrammatic view of another form of our invention applied to a cylinder or drum type of fabric printing apparatus; and

Fig. 5 is a fragmentary end elevation of a modification in the mounting for the independent printing and pressure rollers.

Referring to Fig. 1, the numeral 5 designates a roller which carries the fabric 6 to be printed upon, and 7 designates the roller carrying the backing cloth 8. Both webs are fed upward between guide rollers 9, brought together as they pass over upper guide rollers 10, and then are fed downwardly over roller 11 and around the cylinder 12, which is driven by any suitable source of power such as an electric motor, not shown. The usual apron or blanket 13 is trained around and against cylinder 12 and guide rollers 14. The impression or printing rolls 15, of which there may be any number, are located around the cylinder 12 for contact with the fabric and are of known construction and operation, as also are the winding rolls 16 on which the backing cloth is wound after the printing. The printed cloth 6 after leaving the printing rolls 15 is fed up through a drying chamber designated generally by the numeral 17, being fed therein over and around the drying cans or drums 18 and guide rollers 19 and 20, then to the winding apparatus, designated generally by the numeral 22. All of the foregoing parts are of known construction, and have been in general commercial use.

Obviously the apparatus above generally described is adapted for use in printing only one web at one time, either in a single or multi-colors according to how many of the printing rollers 15 are operatively associated with the cylinder 12. Our invention resides in providing additional apparatus to effect the printing of additional webs of fabric simultaneously with the web 6 and effecting separation of the individual webs during and immediately after the printing and drying. To this end we provide rollers 5' and 7' similar to the rollers 5 and 7, and receiving, respectively, a web 6' and a backing cloth 8' which are fed around guide rollers 9' and brought together over the roller 10'. Adjacent and above the cylinder 12 we provide a roller 23 across which the webs 6' and 8' move downwardly between printing rollers 24 and pressure rollers 25. When the web 6' and backing cloth 8' leave the rollers 24 and 25 they pass downwardly around a guide roller 26 and beneath a platform 27, on which the operator may stand to inspect the web 6,

and at the other end of the platform the web and backing cloth pass around the guide roller 28 and thereabove a guide roller 29. The backing cloth 8' moves around the roller 29 and down to the winding apparatus 30, while the printed fabric or web 6' moves up from roller 28 into the drying chamber 17 and then across cans or drums 18' and guide rollers 19' and 20', all similar to the parts 18, 19 and 20. From the drying chamber the web 6' passes to winding apparatus identical with the winding apparatus 22, but not shown. It will be noted from the above general description and diagrammatic illustration of Fig. 1, that the invention provides a method for simultaneously printing a plurality of webs of fabric by simultaneously advancing the webs, each with a backing cloth, and separating the respective pairs of webs and backing cloths as they are advanced while imparting to the respective webs printed impressions either in single or multi-color, either identical with, or different from each other, according to the printing rolls, and maintaining the webs from contact with each other after the printing and during the drying.

In Figs. 2 and 3 we have shown more in detail the construction and arrangement of the printing mechanism and wherein the cylinder 12 is mounted on a shaft 32 driven by any suitable means such as an electric motor, the shaft being journaled in the ends 33 of the machine, which are mounted upon the base 34. Each of the ends is provided with a plurality of extensions or brackets 36 between which are the color boxes or pots provided with the usual means for feeding the paste or die to the printing rollers 38, which are rotatably supported between the brackets 36 on shafts 39, the ends of which extend beyond the printing surfaces of the rollers and are journaled in adjustable bearing blocks provided in the brackets 36. Screws 37 are mounted through the ends of the brackets 36 to adjust the positions of the blocks and to regulate the pressure of the printing rollers 38 relative to the cylinder 12 and the fabrics therebetween.

In the present embodiment of the invention we have illustrated four rollers 38 cooperating with the cylinder 12 to print the fabric passing therebetween, but of course there may be more or less of the rollers co-operating with the cylinder, and the number of active printing rolls so co-operating may be regulated at will.

Referring to Fig. 3, we have shown a relatively large gear 41, keyed on the shaft 32 and having its teeth in mesh with a smaller gear 42 keyed to a shaft 43, which is provided with sprockets 44. A sprocket chain 45 is trained around one of the sprockets 44 and another sprocket 46 on the shaft 47 which carries the upper roller 24. The lower roller 24 is keyed to a shaft 58 which carries a sprocket 51, around which, and the sprocket 52 on the shaft 47, is trained a chain 53. Obviously, the rotation of the cylinder effects rotation of the gears 41 and 42 and consequently simultaneous rotation of the shafts 43 and 47, through the medium of the sprockets 44, 46 and chain 45. Also the rotation of the shaft 47 through the medium of the sprockets 51, 52 and chain 53, effects rotation of the shaft 58 and consequently rollers 24. The ratio of the gears and sprockets is such as to effect a predetermined synchronized rotation of the rollers 24 and 28 relative to the cylinder 12, and the printing rollers 38.

Referring again to Fig. 2 it will be seen that

the extensions or brackets 36', which correspond to the extensions or brackets 36, carry the color boxes, and the shafts 47 and 50, on which the separate printing rollers 24, shown diagrammatically in Fig. 1, are journaled. Shafts 54, 5 are spaced from the cylinder 12, carry pressure rollers 25. This spacing of the rollers 25 from the cylinder 12 partly effects the separation of the webs being printed, and also provides for the separate printing of the two webs by a single operation and on a single machine. Obviously any desired number of brackets 36' may be provided or utilized in connection with printing rollers 24 in printing the web 6'; and the printing rollers 15 may be interchanged at will and rollers of different size and containing different patterns may be used.

It should also be noted that the pressure rollers 25, spacer blocks 55 and shafts 54 can be removed from the brackets 36', 36' and print rollers 24, 24 can be substituted therefor to print additional patterns or colors on the web 6. Thus, the machine may be used alternatively as a six color or six pattern machine to print one web or may be used to print two webs in the manner shown in Fig. 1.

Furthermore, more than two webs may be simultaneously printed in accordance with the invention, by providing additional rollers printing independently of the cylinder. This latter feature will be better understood after considering a modification of the invention about to be described.

Referring to Fig. 4 it will be noted that there are a plurality of rollers 60, 60' and 60'' containing or having wound thereon the fabrics to be printed, and designated respectively as F, F' and F''. There are also a corresponding number of rollers 61, 61' and 61'', having wound thereon the backing cloth B, B', B'', respectively. These fabrics and backing cloths are arranged in pairs the same as the fabrics and backings of Fig. 1, that is, the webs F and B pass to one set of printing elements, the webs F' and B' to another set of printing elements, and the webs F'' and B'' to another set of printing elements. Of course this is illustrative of how more than two webs may be printed simultaneously, and it is to be understood that any number of webs more than three can be printed simultaneously by arranging the printing elements and the driving mechanism therefor.

In the embodiment of the invention being described the fabric F and backing cloth B pass over a guide roller 62; and the fabric F' and 55 backing cloth B' pass over a similar guide roller 63, while the third web of fabric F'' and backing cloth B'' pass over the guide roller 64. As shown, all of the guide rollers are arranged above the rollers from which the fabrics and backing 60 cloths are fed. The respective pairs of webs of fabrics and backing cloths pass from the guide rolls 62, 63 and 64 over a common guide roller 65 located above and adjacent the cylinder 12'', which may be driven in the same manner as explained in connection with cylinder 12, Figs. 1-3. After leaving the guide roll 65 the respective pairs of fabrics and backing cloths pass downwardly between the cylinder 12'' and the roller 66 adjacent which point the respective pairs of fabrics 70 and backing cloths are separated and printed. The fabric F and backing cloth B pass from the roller 66 between the pressure roller 67 and a printing roller 68, or between a pair or more of such printing and pressure rollers as desired. 75

The printing roller 68 has its shaft connected to a sprocket 69 driven by a chain 70 from one of the sprockets 44 shown in Fig. 3, and designated in Fig. 4 by the numeral 44'. The fabric F'' and backing cloth B' move between the roller 66 and cylinder 12'' out of contact with the pressure roller 67, which of course is spaced from the cylinder 12'', and between printing roller 71' and pressure roller 71, which has keyed to its shaft 10 a sprocket 72. A second chain 73 is trained around sprocket 72 and another of the sprockets 44 and also designated in the diagrammatic view of Fig. 4 as 44'. Of course each of the shafts driving the rollers 68 and 71 may be equipped with 15 double sprockets when more than one printing roller is used for each of the fabrics to receive chains 69' and 72' to drive the other printing and pressure rollers.

The fabric F'' and backing cloth B'' continue 20 around the cylinder 12'' and pass between printing rollers 38' corresponding to the printing rollers 38 of Fig. 2, so that three webs of fabric are simultaneously printed on the same machine either in the same design or pattern or color or 25 colors, or in different designs or patterns and colors. The patterns of course depend upon the engraving on the printing rollers, and the colors depend upon the dies which are fed to the printing rollers. Furthermore, while we have 30 shown in Fig. 4 two sets of printing rollers for each fabric, it should be obvious that there may be one set or any number more than two for each set, or different numbers of rollers for each set. For instance, the fabric F may be subjected to 35 the printing action of three rollers, while the fabric F' may be subjected to the action of from one to more than three, while the fabric F'' may be subjected to the printing action of one, two, or more rollers. This is purely illustrative, as 40 the various combinations are practically inexhaustible.

As the webs are printed, the fabric F'' passes upwardly from the cylinder across a guide roller 75 to the drying chamber and a drying and winding mechanism such as the chamber 17 and the drums and rollers 18, 19 and 20 of Fig. 1. The fabrics F' and F pass downwardly from their printing rollers and around guide rollers 76 and 77, respectively, and then horizontally beneath 50 a platform P, at the other end of which the fabric F' and its backing cloth pass around the guide roller 78. The fabric F' then moves across guide roller 79 to the drying chamber and its drying mechanism. The fabric F and backing 55 cloth B continue beyond the roller 78 and pass around a guide roller 80 at the far end of a second platform P' located between drums 81 and 82 on which the backing cloths B' and B are wound. The fabric F continues up and across the 60 guide roller 83 to its set of drying drums and winding mechanism. The backing cloth F is wound on the drum 82 after passing over the guide roll 83, while the backing cloth F' is wound on the drum 81 after passing over guide roller 65 78; and the backing cloth B'' is wound on the drum or roller 84 after passing around the guide roller 75 and another guide roller 85.

The operator may stand on the platform P to inspect the printing on fabric F'' and on the 70 platform P' to inspect fabric F', or at one side to inspect all simultaneously.

Under the embodiment of the invention shown and described in detail in Fig. 2, the brackets 36' 75 adjustably support the auxiliary printing and pressure rollers, and fixed filler blocks 55 of pre-

determined dimensions according to the size of the rollers are used. However, we have shown in Fig. 5 a modification in the means for spacing the auxiliary rollers from the main cylinder and providing a simple mechanism which is adjustable not only to accommodate rollers of different sizes but also to provide a take-up on the pressure rollers which are subjected to wear.

In Fig. 5 the primed numerals designate the same parts as in Fig. 2 with the exception of 36'' which designates one of the brackets corresponding to brackets 36' of Fig. 2, and supporting the auxiliary rollers. The bearings 90 which support the pressure rollers 25' abut a block 91 having an arcuate face 92 corresponding in curvature to the circumference of the bearings 90. A collar 93 is keyed to a screw 94 as indicated at 95. The inner end of the bracket 36 is provided with a square opening or socket 96 which receives a nut 97 having preferably squared screw threads 10 to mesh with the threads of the screw 94. Obviously, rotation of the screw 94 will cause rotation of the collar 93, and consequently will regulate the pressure on the bearings 90 for the pressure rollers 25'.

25

What is claimed is:

1. Apparatus for simultaneously printing a plurality of webs of fabric comprising a rotary cylinder, means to rotate the cylinder, a group of printing rollers cooperating with the periphery of the cylinder to print a web of fabric passing therebetween, a second group of printing rollers spaced from said cylinder to print another web of fabric passing between said second group of rollers, means operable by rotation of said cylinder to rotate said second group of rollers and to advance the second web of fabric therebetween at the same speed as said first web, supporting racks located substantially at floor level to removably and rotatively support a plurality of rolls 30 of webs of fabric to be printed and backing cloths therefor, separate guiding means above said racks for bringing each web of fabric to be printed and its companion web of backing cloth together in sets to a common point adjacent said cylinder, 35 one of said sets contacting the cylinder and passing partly therearound under said first rollers, and the other set being guided away from said first set and between said second rollers.

2. Apparatus for simultaneously printing a 50 plurality of webs of fabric comprising a rotary cylinder, means to rotate the cylinder, a group of printing rollers cooperating with the periphery of the cylinder to print a web of fabric passing therebetween, a second group of printing 55 rollers spaced from said cylinder to print another web of fabric passing between said second group of rollers, means operable by rotation of said cylinder to rotate said second group of rollers and to advance the second web of fabric therebetween at the same speed as said first web, supporting racks located substantially at floor level to removably and rotatively support a plurality of rolls of webs of fabric to be printed and backing cloths therefor, separate guiding means above 60 said racks for bringing each web of fabric to be printed and its companion web of backing cloth together in sets to a common point adjacent said cylinder, one of said sets contacting the cylinder and passing partly therearound under 65 said first rollers, and the other set being guided away from said first set and between said second rollers, two sets of drying cans located beyond the printing apparatus, and means for guiding said printed webs to said drying cans in spaced 70 75

relation to each other and for training one web partially about the peripheries of one set of drying cans and the other web partially about the peripheries of the other set of drying cans.

3. Apparatus for printing webs of fabric comprising a printing machine having an impression cylinder, means to rotate said cylinder, a frame having a plurality of brackets for supporting printing rollers, a group of printing rollers mounted in certain of said brackets and cooperating with a portion of the periphery of said cylinder and rotated thereby to print a web of fabric passing between said rollers and cylinder, a second group of cooperating printing and impression rollers mounted in others of said brackets and spaced from the periphery of said cylinder, means in said second group of brackets for spacing said second group of printing and impression rollers from said cylinder, positive driving connections between said group of printing and impression rollers and said cylinder driving means whereby all of said rollers are rotated simultaneously to advance the respective webs of fabric at substantially the same speed, and means for guiding and training two separate sets of webs to be printed, each with an associated backing cloth, from separate sources of supply, one set partially around the impression cylinder and in association with the first named printing rollers, and the other set between the second group of printing and impression rollers.

4. Apparatus for printing webs of fabric comprising a printing machine having an impression cylinder, means to rotate said cylinder, a frame having a plurality of brackets for supporting printing rollers, a group of printing rollers mounted in certain of said brackets and cooperating with a portion of the periphery of said cylinder and rotated thereby to print a web of fabric passing between said rollers and cylinder, a second group of cooperating printing and impression rollers mounted in others of said brackets and spaced from the periphery of said cylinder, means in said second group of brackets for spacing said second group of printing and impression rollers from said cylinder, positive driving connections between said group of printing and impression rollers and said cylinder driving means whereby all of said rollers are rotated

simultaneously to advance the respective webs of fabric at substantially the same speed, and means for guiding and training two separate sets of webs to be printed, each with an associated backing cloth, from separate sources of supply, one set partially around the impression cylinder and in association with the first named printing rollers, and the other set between the second group of printing and impression rollers, said group of printing rollers and said second group of printing and impression rollers being interchangeable in said brackets.

5. Apparatus for printing webs of fabric comprising a printing machine having an impression cylinder, means to rotate said cylinder, a frame having a plurality of brackets for supporting printing rollers, a group of printing rollers mounted in certain of said brackets and cooperating with a portion of a periphery of said cylinder and rotated thereby to print a web of fabric passing between said rollers and cylinder, a second group of cooperating printing and impression rollers mounted in others of said brackets and spaced from the periphery of said cylinder, means in said second group of brackets for spacing said second group of printing and impression rollers from said cylinder, positive driving connections between said group of printing and impression rollers and said cylinder driving means whereby all of said rollers are rotated simultaneously to advance the respective webs of fabric at substantially the same speed, and means for guiding and training two separate sets of webs to be printed, each with an associated backing cloth, from separate sources of supply, one set partially around the impression cylinder and in association with the first named printing rollers, and the other set between the second group of printing and impression rollers, two sets of drying cans located beyond the printing apparatus and means for guiding said printed webs to said drying cans in spaced relation to each other and for training one web partially about the peripheries of one set of drying cans and the other web partially about the peripheries of the other set of drying cans.
